REFRIGERATING APPARATUS

Lester E. Perrine, Detroit, Mich., and Charles L. Paulus, Dayton, Ohio, assignors to General Motors Corporation, a corporation of Delaware

Application September 1, 1934, Serial No. 742,490

9 Claims. (Cl. 74—230.17)

This invention relates to refrigeration and more particularly to refrigerating apparatus for conditioning air in vehicles and the like.

It is among the objects of this invention to provide a refrigerating apparatus which may be connected to rotating parts of the vehicle and which causes the refrigerating apparatus to be operated at proper speeds under varying speed conditions of the vehicle.

10 Further objects and advantages of the present invention will be apparent from the following description, reference being had to the accompanying drawings, wherein a preferred form of the present invention is clearly shown.

15 In the drawings:

Fig. 1 is a plan view, somewhat diagrammatic, of a portion of an apparatus embodying features of the invention with one of the shafts horizontally displaced to expose the same to view;

20 Fig. 2 is a vertical view of the apparatus shown in Fig. 1, but with two of the shafts shown in vertical alignment;

Fig. 3 is a view transverse to Fig. 2;

Fig. 4 is a cross-sectional view of the driven 25 pulley portion of the variable ratio drive;

Fig. 5 is a cross-sectional view of the driving member of the variable ratio drive;

Fig. 6 is a view of a portion of the apparatus shown in Fig. 5, but in a different position;

30 Fig. 7 is a portion of the apparatus shown in Fig. 4 but in a different position;

Fig. 8 is a cross-sectional view taken substantially along the line 8—8 of Fig. 4; and

Fig. 9 is an enlarged cross-sectional view taken 35 along the line 9—9 of Fig. 4.

In practicing this invention, a vehicle is provided with a variable ratio drive by which an apparatus, such as a compressor 10 of an air conditioning system, is driven at desired or permissible speeds notwithstanding the variations in the speed of travel of the vehicle. Preferably the variable ratio drive is interposed between the compressor and some rotating part of the vehicle which rotates in direct proportion to the speed of the vehicle. For example, the rotating part may be an axle 11 which carries a wheel 12 of the vehicle. The axle 11 actuates the driver portion 13 of the variable ratio drive which in turn drives the driven portion 14 of the variable ratio drive from whence the power is transmitted by suitable instrumentalities to the compressor 10.

When this invention is applied to a railway car or the like, the axle 11 is preferably caused to drive a jack-shaft 15 floatingly mounted on the vehicle by means of hangers 16. The drive be-

tween the axle 11 and the shaft 15 preferably takes the form of the belt drive 17 which drives the jack-shaft 15 at a greater rotational speed than the axle 11. The drive 17 may be of the multiple V-belt type as shown having pulleys 17a and 17b on which the belts 17c operate.

The driven portion 14 of the variable speed drive may be mounted on a shaft 18 which in turn drives the compressor 10 through the medium of belts 19 interposed between the pulley 20 of the shaft 18 and the pulley 21 of the compressor 10. If desired, the shaft 18 may form a portion of the dynamo electric machine 22 hereinafter more fully described.

The variable ratio drive preferably includes 15 frictionally connected rotating parts having variable effective power transmitting diameters and is provided with means for automatically varying these diameters to compensate for variations in the speed of travel of the vehicle. These 20 frictionally connected rotating parts preferably take the form of one or more driving pulleys 23 and one or more driven pulleys 24 between which are placed one or more belts 25. One or more of the pulleys is provided with relatively movable 25 flanges, the relative movement of which varies the effective belt diameter of the pulley or pulleys and thus varies the speed ratio between the axle 11 and the compressor 10.

In the preferred embodiment, the driving member 30 includes a pair of pulleys 23 each of which is provided with an axially fixed pair of cone-shaped flanges 30 and 31 and a pair of axially movable cone-shaped flanges 32 and 33. The flanges 30 and 31 are directed in one axial direction and the flanges 32 and 33 are directed in the opposite axial direction thus to form the V-pulleys 23. Means are provided for automatically moving at least one of the pairs of flanges, such as flanges 32 and 33, in a manner to be more 40 fully described in order to vary the effective belt drive diameter. This variation in diameter causes the belts 17 to ride far out on the pulley as shown in Fig. 5 or nearer towards the center as shown in Fig. 6.

The driven portion of the variable drive 14 (shown more in detail in Figs. 4, 7, 8 and 9) is preferably also provided with a pair of pulleys 24. These pulleys are formed by relatively movable conical-shaped flanges somewhat similar to 50 the driving member 13. Thus axially fixed flanges 40 and 41 are directed in the same general axial direction while the movable flanges 42 and 43 are directed in the opposite axial direction to form V-shaped grooves or pulleys. Here also

automatic means are provided for causing relative movement between these flanges thus to cause the belts 25 to move axially inwardly or outwardly to vary the effective belt diameter.

5 The means for automatically varying the effective belt diameters of the pulleys preferably is speed responsive in character. Thus one or more centrifugal devices 45 are placed on either the driving member or the driven member to vary 10 these diameters. In the preferred form, a plurality of centrifugal devices or rollers 45 are placed on the driven member 14. These centrifugal devices take the form of roller-like weights having independently movable frictional 15 contact surfaces 46 and 47 which engage the slanting surfaces 48 and 49. When the centrifugal devices 45 fly outwardly they spread the flanges 40 and 43 apart as indicated in Fig. 7, thus moving flanges 43 and 42 to the position 20 shown in Fig. 7 to vary the effective belt driving diameter.

The flanges 42 and 43 are tied together by means of sleeves 50 which are secured to these flanges and which ride on antifrictional devices 25 51 on the bolts 52 which are supported between the flanges 41 and the hub 60. The fixed flanges 40 and 41 are maintained in their fixed spaced positions by bolts 52a having enlarged portions 52b which together with the sleeves 52c lock the 30 flanges 40 and 41 in their fixed relation. The entire pulley structure is locked to the hub 60 and is floatingly mounted on the shaft 18 by ball bearings 24a and 24b.

When the belts 17 move outwardly from the 35 position shown in Fig. 4 to the position shown in Fig. 7 the tension on the belts causes them to move inwardly on the driving member 13 from the position shown in Fig. 5 to the position shown in Fig. 6. Automatic means are provided 40 for accomplishing this latter movement of the belt, and this automatic means preferably takes the form of a tensioning device or belt take-up now more fully described. A helical spring 53 is adjustably held by the nut 54 against a housing 45 55. This housing 55 is connected to the movable flange 33 by bolts 56, while the movable flange 33 is tied to the movable flange 32 by the sleeves 57 which ride on any antifrictional device 58 carried on the bolts 59. The auxiliary fixed flange 50 30 is tied to the fixed flange 31 by means of bolts 61 having enlarged portions 62 and sleeves 63 cooperating with a sleeve 64 keyed to the shaft 15. The bolts 59 and 61 are supported on the flange 30 which is also keyed on the shaft 15. 55 Thus as the housing 55 is urged axially against the movable flanges 32 and 33 by the spring 53, the flanges 32 and 33 are permitted to move in response to varying tensions of the belt. By adjustment of the nut 54 the spring tension may be 60 balanced with the force created by the centrifugal device 45 to obtain the desired variable ratio. The adjustment may be carried to such an extent that the shaft 18 is driven at a substantially constant speed regardless of variations in the car speed between any desired speed limits. It is to 65 be understood, however, that the adjustment need not be carried further than to maintain the speed of shaft 18 between permissible limits rather than at a substantially constant speed.

70 The detailed construction of the centrifugal weights 45 will be more readily understood by reference to Figs. 4, 7, 8 and 9. Each of the weights 45 is a roller-like construction mounted on bolts 65 with antifriction devices 46 riding 75 loosely on the bolts 65. The devices 46 are spaced

by the antifriction device 47 which is formed by a cylindrical member having a plurality of holes 66 bored therein, this cylinder having smaller cylindrical protrusions 67 extending into the cup-like formations of the devices 46. One of the 5 pulley flanges, such as flange 40, is provided with a stepped surface 49 adapted to cooperate with the antifriction device 47 while the flange 43 is provided with stepped surfaces 48 adapted to cooperate with the antifriction devices 46 of the 10 centrifugal weight 45. Thus the device 47 rolls on surface 49 in one direction while the devices 46 roll on the surface 48 in the other direction. This permits the centrifugal weights 45 to move radially inwardly or outwardly with very little 15 resistance due to friction against the pulley flanges.

Clutch means are provided permitting the compressor to be declutched from the axle 11 when the car is standing still or is running at 20 speeds too low or too fast which are beyond the range of operation of the ratio changing device. In the preferred form, the clutch means cooperates with a flange 73 to clutch the edge of the disc 70. When the flanges 72 and 73 are brought 25 together by the springs 74, the pulleys 24 are clutched to the shaft 18. When the flanges 72 and 73 are spread apart, the pulleys 24 are declutched from the shaft 18. This clutching and declutching operation thus affects the drive in 30 the shaft 11 and the compressor 10.

Pneumatic means are provided for actuating the clutch means. Thus a diaphragm 75 is provided at one edge of the chamber 76 which is connected by the opening 77 with the air brake 35 system. When pneumatic pressure is introduced into the chamber 76, the diaphragm 75 is pressed against the ring 78 which ring rides against the ball bearing 79. The reaction thus produced moves the casing 80 towards the left in Fig. 4 40 and this in turn carries the thrust bearing 81 in the same direction and with it the flange structure 73 thus spreading apart the flanges 72 and 73. When the pneumatic pressure is relieved in the chamber 76, the springs 74 are permitted to 45 clamp the clutch disc 70 between the flanges 72 and 73. Suitable control means may be provided for controlling the flow of air into the chamber 76.

The discharge from compressor 10, such as 50 compressed refrigerant, may enter condensers 85 and 86 which are mounted on the ends of a box structure 87 which is substantially air-tight except at the edges 88 and 89 and at the opening 90 where a fan 91 is placed. The fan 91 is of 55 such a construction that when rotated in one direction it blows air inwardly into the box 87 through opening 90 and when it is rotated in an opposite direction it blows air outwardly from the box 87 through opening 90. When the air is 60 thus blown inwardly into the box, the air leaves through the condensers and is discharged into the atmosphere along the edges 88 and 89 thus cooling the condensers. When the air is blown outwardly by the fan, the air enters the box 87 65 through the condensers along the edges 88 and 89 and goes out through the opening 90. The fan 91 may be driven by any suitable means such as by belts 92 driven from a shaft 93 which in turn is driven by belts 94 from the pulley 20.

The compressor may be supported under the car in any suitable manner. Thus downwardly directed bolts 95 support the compressor 10 at the bottom thereof. Suitable brace bolts 96 prevent the compressor from swaying. The jack-shaft 15, 75

which is swingingly mounted by the brackets 16 is urged away from the axle 11 by a spring 97 as will be readily understood. This provides for any necessary take-up in the belts 17c. By running the shaft 15 at a higher speed than the axle 11, it is possible to run the belts 25 at a relatively high speed and thus the size and number of the parts of the ratio transmitting device are reduced because of the relatively high speed of operation 10 of the parts. The jack-shaft 15 extends through the housing 87 and the necessary opening therefore is sufficiently sealed by a sliding flange construction 98 so that the housing 87 is maintained substantially air-tight except at the edges 88 and 15 89 and opening 90.

By properly calibrating the length and strength of the spring 53 as well as its adjustment by the nut 54, it is possible to coordinate its action with that of the centrifugal means 45 in such a manner that the driven part of the variable ratio drive rotates at a substantially constant speed while the car is travelling at variable speeds but within reasonable limits. The compressor 10 therefore operates at a substantially constant 25 speed and produces refrigeration for the car at a constant rate while the car is travelling at all normal speeds.

When the car is standing still or is operating at an abnormally low or high speed, the compressor 30 may be operated by the dynamo electric machine, which may be energized by battery or station current. During this type of operation, the compressor is declutched from the axle 11.

While the form of embodiment of the invention as herein disclosed, constitutes a preferred form, it is to be understood that other forms might be adopted, all coming within the scope of the claims which follow.

What is claimed is as follows:

40 1. A variable ratio drive including a compound pulley having a shaft, a pair of axially movable, relatively fixed flanges on said shaft, a pair of axially fixed flanges on said shaft, said flanges forming two V-shaped grooves on said pulley, a flange on one of said pairs cooperating with a flange on the other of said pairs to form diverging surfaces, a centrifugal weight between said diverging surfaces and acting to vary the width of said grooves, a plurality of rods around the 45 shaft each supported by the shaft at two separated points, said relatively movable flanges being slidably mounted upon said rods.

2. A variable ratio drive including a driver pulley, a driven pulley, one of said pulleys having 55 a pair of relatively movable flanges, centrifugal means for causing relative movement of said flanges including oppositely directed cone surfaces, a centrifugal weight between said surfaces having independently movable anti-friction devices in contact with said surfaces, a shaft means upon which one of said pulleys is rotatably mounted, and clutch means for connecting said shaft to said one pulley.

3. A variable ratio drive including a driving member, a driven member, a pair of belts between said members, a pair of conically shaped flanges axially fixed on one of said members directed in one direction, and a pair of conically shaped flanges axially fixed with respect to each 65 other and movable on said last named member directed in the opposite direction forming a pair of V-shaped pulleys on said member for said belts, and speed responsive means for axially moving the axially movable pair of flanges to 70 vary the effective belt diameter of said pulleys

including centrifugal means on one of said members and spring means on the other of said members, and externally accessible adjusting means for adjusting the tension of said spring means.

4. A variable ratio drive including a driving member, a driven member, a pair of belts between said members, a pair of conically shaped flanges axially fixed on one of said members directed in one direction, and a pair of conically shaped flanges axially fixed with respect to each other and movable on said last named member directed in the opposite direction forming a pair of V-shaped pulleys on said member for said belts, and speed responsive means for axially moving the axially movable pair of flanges to 15 vary the effective belt diameter of said pulleys, including centrifugal means on one of said members and spring means on the other of said members, one of said pulleys being rotatably mounted upon one of said members, and clutch means for 20 connecting said rotatably mounted pulley to its member.

5. A variable ratio drive including a driving member, a driven member, a pair of belts between said members, a pair of conically shaped flanges on one of said members axially fixed with respect to each other directed in one direction and a pair of conically shaped flanges on said last named member axially fixed with respect to each other directed in the opposite direction forming a pair of V-shaped pulleys on said member for said belts, a flange of one pair having a surface outwardly converging with respect to a surface on a flange of the other pair, and speed responsive means for axially moving one of said pair of flanges to 30 vary the effective belt diameter of said pulleys, said speed responsive means including a centrifugally movable structure between and acting on said outwardly converging surfaces, all of the flanges upon one of said members being rotatably mounted thereon, and clutch means for connecting said flanges to said one member.

6. A variable ratio drive including a compound pulley having a shaft, a pair of axially movable, relatively fixed flanges on said shaft, a pair of axially fixed flanges on said shaft, said flanges forming two V-shaped grooves on said pulley, a flange on one of said pairs cooperating with a flange on the other of said pairs to form diverging surfaces, a centrifugal weight between said diverging surfaces and acting to vary the width of said grooves, and clutch means for drivingly connecting and disconnecting said flanges to said shaft.

7. A variable ratio drive including a driving member, a driven member, a pair of belts between said members, a pair of conically shaped flanges axially fixed on one of said members directed in one direction, and a pair of conically shaped flanges axially fixed with respect to each other and movable on said last named member directed in the opposite direction forming a pair of V-shaped pulleys on said member for said belts, and speed responsive means for axially moving the axially movable pair of flanges to vary the 55 effective belt diameter of said pulleys including centrifugal means on one of said members and spring means on the other of said members.

8. A variable ratio drive including a driving member, a driven member, a pair of belts between 70 said members, a pair of conically shaped flanges on one of said members axially fixed with respect to each other directed in one direction and a pair of conically shaped flanges on said last named member axially fixed with respect to 75

each other directed in the opposite direction forming a pair of V-shaped pulleys on said member for said belts, a flange on one pair having a surface outwardly converging with respect to a surface on a flange of the other pair, and speed responsive means for axially moving one of said pair of flanges to vary the effective belt diameter of said pulleys, said speed responsive means including a centrifugally movable structure between and acting on said outwardly converging surfaces.

9. A variable ratio drive including a compound

5 pulley having a shaft, a pair of axially movable, relatively fixed flanges on said shaft, a pair of axially fixed flanges on said shaft, said flanges forming two V-shaped grooves on said pulley, a flange on one of said pairs cooperating with a flange on the other of said pairs to form diverging surfaces, a centrifugal weight between said diverging surfaces and acting to vary the width of said grooves.
